METHOD OF MAKING PICTURE FRAMES

John Wesley Berg, Denver, Colo.

Application November 17, 1947, Serial No. 786,480

8 Claims. (Cl. 18—56)

1

This invention relates to improvements in the method of making picture frames.

Picture post cards are sold in all parts of the country and are purchased in great numbers by tourists and others. Such cards usually depict some interesting scenery or some famous buildings and are oftentimes real works of art.

At present it is customary to vend such cards in the form of rectangular cardboards having the pictures on one side and space for message, address and postage stamp on the other side.

Since so many picture post cards are highly artistic, ornamental and of general interest, many people desire to preserve them.

It is the object of this invention to produce an inexpensive, but highly ornamental and practical frame for use more particularly with picture post cards, in which post cards of special interest may be mounted, thus increasing their ornamental and artistic appearance and effect.

The frame, briefly described, consists of a piece of heavy paper having one surface finished and provided with suitable designs, formed into a shape in which the center is flat and in which the edges are subjected to a treatment by means of dies, chemicals and heat, so as to form an outer border of concavo convex cross section having the appearance of a picture frame molding. The picture post card is secured to the flat center portion by a suitable adhesive.

Another object is to produce a method by means of which pieces of paper of the proper shape and size may be formed with ornamental embossed edges that will retain their shape and will not be affected by climatic conditions.

Having thus explained the objects of the invention, and in a general way, the invention itself, the invention will now be described in detail, and for this purpose reference will be had to the accompanying drawing in which it has been illustrated, and in which:

Figure 1 is a front elevation showing the invention with a picture post card mounted therein;

Figure 2 is a rear view of a portion of the paper sheet from which the frame is made, showing the zone that has been moistened with a thermo hardening plastic solution;

Fig. 3 is a section taken on lines 3—3, before the post card has been positioned in the frame;

Figure 4 is a section similar to that shown in Figure 3, but shows the post card in position; and

Figure 5 is a side elevation, partly in section, showing a simple apparatus for carrying out the method.

In the drawing reference numeral 10 designates a sheet of stiff paper, usually rectangular in shape, and of a size larger than the post card or picture that is to be secured thereto. In Figure 2, the unshaded portion represents a portion of the surface to which the picture is to be adhesively secured and the shaded portion 11, the zone or area that extends beyond the picture and which is to be moistened by a thermo hardening plastic and formed by dies into picture molding

2

shape. The picture post card has been designated by numeral 12.

In order to form the paper sheet into a frame, by means of dies, it is necessary to moisten those areas that are to be shaped by the dies, in order that the material may be deformed without breaking or tearing. The moistening might be accomplished by immersing the edges of the sheet in water, preferably hot, and then subjecting it to a forming operation. If such a water moistened sheet is allowed to dry while in position between forming dies, it will assume the shape shown, but it will not retain that shape indefinitely. Aside from the fact that the desired shape is temporary only, the formed edges will be weak and easily torn or deformed.

In order to make a frame that will retain its shape and have sufficient strength to resist the various forces to which it is subjected in handling, it is essential that the edges shall be so treated that they will become harder and stronger after the treatment. For the purpose of hardening and strengthening the edges, the solution with which they are moistened must possess such properties that it will harden during the forming and drying operation, leaving the edges harder and stronger than the original paper.

It has been found that the desired results are obtained by moistening the edges of the paper sheet with a solution containing one of several thermo hardening plastics, preferably a thermo setting plastic. There are on the market today a number of thermo hardening and thermo setting plastics that may be obtained in liquid form.

Among the several plastics that may be employed for this purpose are "Bakelite," a phenol formaldehyde; nitrocellulose; acrylic plastics such as methyl methacrylate; and acrylic resins, generally known as Lucite and Plexiglas. In addition to the plastics above mentioned resorcinol formaldehyde and urea formaldehyde may be used, both of which are thermo hardening.

One solution suitable for the purpose under consideration comprises:

	Parts
Polychloroprene	100
Resorcinol	26
Formaldehyde (37%)	12.3
Sodium hydroxide	2

Such a solution will readily permeate paper and hardens when subjected to heat.

There is on the market today a resorcinol solution sold under the trade name of Resloom 55 M75, manufactured by the Monsanto Chemical Company, the exact ingredients are not known. This solution, however, contains resorcinol and formaldehyde and for applicant's purpose six ounces of Resloom is mixed with one gallon of denatured alcohol after which one teaspoonful of saturated ammonium chloride is added to each pint of the solution.

The paper blanks, after being cut to the proper size and shape, are moistened along their edges

in the solution above identified, or in some similar solution containing a thermo setting plastic. A thermo plastic may be employed, but is not so desirable as a thermo setting plastic. The term "plastic" is used in a sense broad enough to include both the thermo plastic and thermo setting plastics.

It is sufficient if the edges of the paper blank are moistened as shown in the drawing, but it is permissible to immerse the whole sheet in the solution if desired.

After the paper blank has been moistened, it is positioned in the forming machine that is shown in Figure 5, or in a machine of similar construction. The machine illustrated has been shown as an example and may be replaced by any other machine that is suitable for the purpose.

In Figure 5, reference numeral 13 designates a base having at least two guides 14 projecting upwardly therefrom in spaced parallel relation. The upper ends of guides 14 are connected by means of a strong bar 15 to the undersurface of which is secured a die 16 having incorporated therein an electric heating element 17. A cross head 18 is slidable on guides 14, and has removably secured to its upper surface a die 19 that is complementary to die 16. Guides 14 have shoulders at 20 that limit the downward movement of the cross head. Springs 21 urge the crosshead downwardly.

A cylinder 22 is secured to base 13 by bolts 23 and has a removable cylinderhead 24. A piston 25 is mounted in the cylinder and has connected therewith a piston rod 26 whose upper end is connected with the crosshead.

Reference numeral 27 designates a supply of compressed air that is connected with the interior of the cylinder by means of pipes 28 in which is positioned a valve 29 of such construction that when it is in one position, it communicates the interior of the cylinder with the compressed air and when in another position with the atmosphere. Die 19 is provided with a groove 30 that is rectangular and die 16 is provided with ridges 31 that are shaped to fit into grooves 30. The moistened paper blank is positioned on the top of die 19 and valve 29 operates to direct air under pressure into the cylinder whereupon die 19 will move upwardly forcing the ridges 31 into grooves 30 bending the edge of the paper into the shape shown in Figures 3 and 4. The parts are now left until the solution has evaporated and the plastic has set or hardened after which the valve 29 is turned to exhaust position, permitting the parts to return to the position shown in Figure 5. The paper blank now has the form shown in the drawing and the picture post card can then be adhesively secured thereto.

In order to expedite the forming or shaping operation, it is desirable that the solution shall be of such consistency that it will quickly penetrate the paper, and that it shall be volatile. The use of alcohol or diethyl ether is principally for the purpose of obtaining a solution that will evaporate quickly.

Having described the invention what is claimed as new is:

1. The method of forming a picture frame from paper which consists in the steps of cutting a piece of paper to a desired shape and size moistening only the edges of the paper with a solution containing a thermosetting plastic and a volatile liquid solvent, subjecting the moistened

piece to a forming action of dies, the forming action altering the edges to produce a beaded non-planar cross section of uniform thickness, the central portion surrounded by the beaded edges being retained planar and the beaded edge being formed with all corresponding portions thereof lying in a plane substantially parallel to the plane of the central portion surrounding same outwardly thereof, subjecting the paper

10 while in the forming dies to heat, the heat producing volatilization of the liquid solvent and hardening of the plastic to a rigid relatively undeformable state, and adhesively securing a picture to the central portion.

15 2. The method as defined by claim 1 wherein said edges are moistened with a solution containing resorcinol formaldehyde plastic and alcohol.

3. The method as defined by claim 1 wherein said edges are moistened with a solution containing resorcinol formaldehyde plastic, alcohol, and ammonium chloride.

20 4. The method as defined by claim 1 wherein the forming action produces a rectangular central portion.

25 5. The method as defined by claim 1 wherein the beaded edge is formed to a concavo-convex cross section, the convex side being embossed outwardly from the side of the central portion to which the picture is mounted.

30 6. The method as defined by claim 1 wherein the forming action produces a rectangular central portion surrounded by the beaded edge, the beaded edge being formed to a concavo-convex cross section, the convex side being embossed outwardly from the side of the central portion to which the picture is mounted.

35 7. The method as defined by claim 1 wherein said edges are moistened with a solution containing urea formaldehyde plastic and alcohol.

40 8. The method of forming a picture frame from paper which consists in the steps of cutting a piece of paper to a desired shape and size, moistening only the edges of the paper with a solution containing a thermosetting plastic and a volatile liquid solid, subjecting the moistened piece to a forming action of dies, the forming action producing a rectangular central portion substantially the size of a picture post card, surrounded by beaded edges, the edges being formed to a concavo-convex cross section, the convex side being embossed outwardly from one side of the central portion, and adhesively securing a picture post card to the central portion on the last named side.
